EARRING

William O. Craven, Fullerton, Calif.

Application March 2, 1959, Serial No. 54,786

Term of patent 14 years

(Cl. D45—9)

FIG. 1

FIG. 2

Fig. 1 is a front elevational view of an earring, showing my new design;

Fig. 2 is a side elevational view; and

Fig. 3 is a rear elevational view thereof, with the clip portion being omitted for convenience of illustration.

The dominant features of my design reside in the portion shown in full lines.

I claim:

The ornamental design for an earring, as shown and described.
